COMBINED FILMSTRIP AND SLIDE PROJECTOR OR SIMILAR ARTICLE

Paul John Kilday, Chicago, Ill.

Application April 27, 1954, Serial No. 30,214

Term of patent 14 years

(Cl. D61—1)

FIG. 1

FIG. 2

To all whom it may concern:

Be it known that I, Paul J. Kilday, a citizen of the United States of America, residing at 2434 W. Lunt Avenue, Chicago, State of Illinois, have invented a certain new, original, and ornamental Design for a Combined Filmstrip and Slide Projector or Similar Article, of which the following is a specification, reference being had to the accompanying drawings, forming a part hereof.

Fig. 1 is a front perspective view of a combined filmstrip and slide projector showing my new design.

Fig. 2 is a rear perspective view thereof.

The portion of the side not shown in Fig. 2 is the same as the side shown in Fig. 1.

I claim:

The ornamental design for a combined filmstrip and slide projector or similar article, substantially as shown and described.
